UNITED STATES PATENT OFFICE.

EDWIN S. PIPER, OF BRISTOL, CONNECTICUT, ASSIGNOR, BY MESNE ASSIGNMENTS, TO WALTER E. STRONG, OF SAME PLACE.

BOTTLE-WASHING MACHINE.

SPECIFICATION forming part of Letters Patent No. 337,615, dated March 9, 1886.

Application filed July 28, 1884. Serial No. 139,043. (No model.)

To all whom it may concern:

Be it known that I, EDWIN S. PIPER, residing at Bristol, in the county of Hartford and State of Connecticut, have invented certain new and useful Improvements in Bottle-Washing Apparatus; and I do declare the following to be a full, clear, and exact description of the same, reference being had to the accompanying drawings, which form a part of this specification.

My invention relates to an improvement in apparatus for washing the exterior and interior surfaces of bottles, the object being to provide means for the purpose which shall be simple to construct, easy to operate, efficient in use, and of great capacity for work.

With these ends in view my invention consists in certain details of construction and combinations of parts, as will be hereinafter described, and pointed out in the claims.

In the accompanying drawings, Figure 1 is a plan view of a bottle-washing apparatus embodying my invention. Fig. 2 is a view in side elevation of that portion of the apparatus by which the exterior surfaces of the bottles are washed. Fig. 3 is a similar view of the corresponding portion of the apparatus for washing the interior surfaces of the bottles. Fig. 4 is a view in front elevation of the devices shown in Figs. 2 and 3, and Fig. 5 is a detached perspective view of the expandible device for cleansing the interior surfaces of the bottles.

In the following description the means for washing the exterior surfaces of the bottles will first be considered, and those for washing their interior surfaces afterward.

Stiff brushes A and rubbers B are attached to and alternate upon converging flexible arms C, secured to a revolving drum, D, and forming an open cone-shaped structure somewhat exceeding in length the length of the longest bottles.

The function of the brushes is to cleanse the bodies of the bottles, which work they perform thoroughly by virtue of being pressed against the surfaces to be cleansed by the action of the flexible arms, which are preferably made of heavy spring steel.

The function of the rubbers is to cleanse the 50 necks of the bottles, and also to support the outer ends of the same. For this purpose the arms to which they are attached are somewhat longer than those to which the brushes are secured, and the rubbers are attached at right 55 angles to the ends of the arms, and have their inner edges cut away to conform to the contour of the surfaces to be embraced by them. As herein shown, four brushes and as many rubbers are employed; but this number may 60 be changed, if desired. The drum aforesaid is secured to a hollow shaft, E, journaled in bearings F, secured to the bed G of the apparatus. The said shaft is secured against lateral displacement by collars H, and provided 65 with two cone-pulleys, I and J, the former being connected with any convenient source of power, and the latter transmitting a portion of the power to the apparatus for cleansing the exterior surfaces of the bottles. 70

A movable rod, K, extending through the shaft aforesaid, and into the forward end of the cone-shaped structure already described, is provided at its forward end with a flaring and shallow cup, L, in which the bottles are 75 centered and supported, and at its rear end with an adjustable sleeve, M, having a hollow arm, N, inclosing a spring, O, and a dog, P, which latter engages with the bifurcated outer end of an arm, Q, controlling the valve 80 R of the pipe S, which is connected with the water-main T through an arm, U, as shown. The said pipe S is supported in a standard, V, secured to the base of the machine, and extends forward in position to throw water in 85 fine jets upon the brushes and rubbers and the bottles introduced between them. A weight, W, attached to a cord, X, running over pulleys Y and Z and connected with the rod K, which end of the rod is journaled in an arm, A', sustains the rod in its normal position, in which the cup L is located just within the rear ends 90 of the brushes, and the valve R closed. In order to insure positiveness of action in opening the said valve, the arm Q is connected with a spring, B', located within a hollow arm, C', secured to the pipe U, and arranged to exert a constant tendency to open the valve. 95

A ring, D', located in front of the cone-shaped structure and secured to the bed of the apparatus, is designed to facilitate the centering of the bottles in the brushes and rubbers, and for this purpose and for use with the smaller sizes of bottles the ring is provided with a supplemental ring, E', which is secured in place by buttons F' or equivalent means. The ring D' also serves as a support and frame-work for the removable cylindrical covering or shield G', (shown in Fig. 1,) which incloses the cone-shaped structure and the water-pipe.

Having described so much of the apparatus as relates to washing the exterior surfaces of a bottle, I will now proceed to describe the operation of such part.

The bottle to be washed is grasped by its neck and introduced, large end foremost, between the brushes and rubbers, all of which are forced aside to receive it. The bottle is then pressed inward until its neck is embraced by the rubbers, which thus support its outer end. The inner or large end of the bottle is supported meanwhile by the brushes and the cup secured to the rod, which latter was moved back by the bottle during its introduction between the brushes and rubbers, with the effect of opening the valve and allowing numerous jets of water to be thrown upon the brushes, rubbers, and bottle. It will be understood that during all this time the brushes and rubbers are being very rapidly revolved and operated to thoroughly cleanse the body and neck of the bottle. When cleansed, the bottle is withdrawn, and as this is done the weight operates to move the rod forward to its normal position, in which the valve is closed and the cup stationed just to the rear of the brushes, to be again engaged for moving the rod back when the next bottle is introduced.

That part of the apparatus for washing the interior surfaces of the bottles consists, essentially, of an expansible scrubbing device and means for contracting the same and for controlling a supply of water which is sprayed into the bottle through the said device while its interior surfaces are being scrubbed. The expansible scrubbing device consists of a stock, G³, preferably formed from a piece of tubing having a thread cut on its rear end and its forward end cut down in tapering form, a pair of spring-arms, H', provided with ribbed rubber covers I', and respectively secured to and folding upon the tapering sides of the stock, and a brush, J', formed of bristles, which are drawn through a block, K', located in the forward end of the stock and wired to a pin, L', situated in the stock, as shown. The threaded end of the stock screws into the forward end of a hollow shaft, M', which is secured to a similar shaft, N', journaled in bearings O', attached to the bed of the apparatus. The said shaft N' is prevented from lateral play in its bearings by means of collars P', and provided with a cone-pulley, Q', which is connected by a belt, R', with the pulley J of

the mechanism for washing the exterior surfaces of the bottles. The expansible scrubbing device is contracted for introduction into the bottles by means of a movable contractor consisting of a sleeve, S', having a flaring or cup-shaped outer end and journaled in the arm T' of the carriage U', and secured in place in the said arm by means of a collar, V', as shown. By virtue of this construction and arrangement of parts the contractor rotates with the scrubbing device, when closed over the same by reason of the frictional coupling between them, due to the expansive action of the spring-arms and brush. This avoids all wear upon the said arms and brush when not in active operation. The scrubbing device is steadied after its introduction into a bottle and while rapidly revolving, by the carriage aforesaid, and through the contractor, which is journaled therein and embraces the shaft to which the said device is secured, the carriage being supported on either side by rods W', the opposite ends of which are respectively mounted in the ring X', which corresponds to the ring D', hereinbefore referred to, and in a cross-bar, Y', secured to the foremost of the bearings O' of the hollow shaft N', as represented. Water is supplied to the interior of the bottle being cleansed by a small stationary pipe, Z', supported in the standard V', and extending through the shaft N' and forward through the shaft M' to a point just within its forward end. The rear end of the said water-pipe connects with a valve, H², communicating with the water-main I through an arm, B², as shown. The valve H² is controlled by an arm, C², the bifurcated outer end of which is engaged by a dog, D², actuated by a spring, E², and mounted in the hollow arm F² of an adjustable sleeve, G², attached to the rear end of a rod, H², the forward end of which is secured to an arm, I², depending from the carriage. A weight, J², attached to a cord, K², running over pulleys L² and M², and connecting with the rear end of the said rod, is employed for sustaining the same in its normal position, in which the carriage is moved to the limit of its forward travel, the contractor is closed over the expansible scrubbing device, and the valve closed. In order to insure positiveness in the opening action of the valve, the arm C² thereof is connected with a spring, N², located in a hollow arm, O², secured to the rearmost of the standards O', and arranged to exert a constant tendency to open the valve. A shield, P², (shown in Fig. 1, and corresponding to the shield G', referred to,) is employed for inclosing the expansible scrubbing device and the parts more directly associated with it.

Having now described the construction of that portion of my improved apparatus which is designed to wash the interior surfaces of bottles, I will proceed to describe its operation.

The bottle is taken in the hand and held by its body portion, while its mouth is centered in the flaring end of the contractor. This done, the bottle is pressed inward, carrying

the said contractor and carriage and gradually exposing and covering the expansible scrubbing device, which is eventually fully expanded into the bottle, the sides of which are scrubbed by its spring-arms and the bottom of the bottle by the brush. The described movement of the carriage effects, through the rod secured to its depending arm, the opening of the valve, which is followed by a strong discharge of water into the bottle through the scrubbing device. During all this time the said device is being rapidly revolved and assisted by the expansion resulting from the action of centrifugal force in cleansing the interior surfaces of the bottle. When clean, the bottle is withdrawn, and as this is done the carriage and its attachments are restored by the weight to their normal positions and the valve closed.

20 It will be observed that both the devices for washing the exterior and the interior surfaces of the bottles are provided with cone-pulleys, the object being to enable the rate of rotation in both devices to be varied to effect an expansion by centrifugal action suitable to the size of the bottle being cleansed.

It is apparent that some changes in the details of construction of my improved apparatus may be made, and I would therefore have it understood that I do not limit myself to the exact construction and arrangement of parts shown and described, but hold myself at liberty to make such changes and alterations as fairly fall within the spirit and scope of my invention.

Having fully described my invention, what I claim as new, and desire to secure by Letters Patent, is—

1. A machine for cleaning bottles, having scrubbers constructed and arranged for cleaning the outer surfaces of the bottles, and converging spring-arms carrying the said scrubbers, substantially as set forth.

2. A machine for cleaning bottles, having scrubbers constructed and arranged for cleaning the outer surfaces of the bottles, spring-arms carrying the said scrubbers, and a revolving head to which the said arms are attached, substantially as set forth.

3. A machine for cleaning bottles, having scrubbers constructed and arranged for cleaning the outer surfaces of the bottles and grouped to inclose the bottles, and spring-arms carrying the scrubbers, substantially as set forth.

4. A machine for cleaning bottles, having scrubbers constructed and arranged to clean the outer surfaces of the bottles, and including rubbers adapted to clasp the necks of the bottles, substantially as set forth.

5. In a bottle-washing apparatus, means for washing the exterior surfaces of a bottle, consisting of brushes and rubbers respectively mounted upon converging flexible arms, substantially as set forth.

6. In a bottle-washing apparatus, means for washing the exterior surfaces of a bottle, consisting of brushes and rubbers attached to

and alternating upon converging flexible arms, the rubbers being arranged to cleanse the neck of the bottle, substantially as set forth.

7. A machine for cleaning bottles, having scrubbers constructed and arranged for cleaning the outer surfaces of the bottles, and a removable support located within and between the scrubbers for supporting the bottles as the same are advanced between and withdrawn from the scrubbers, substantially as set forth.

8. A machine for cleaning bottles, having scrubbers constructed and arranged for cleaning the outer surfaces of the bottles, a cup situated within and between the scrubbers and located upon a longitudinally-movable rod, and means, substantially as shown, for operating the said rod and cup to support the bottles while they are being advanced between and withdrawn from the scrubbers, substantially as set forth.

9. A machine for cleaning bottles, having scrubbers constructed and arranged for cleaning the outer surfaces of the bottles, a movable support located within and between the scrubbers for supporting the bottles as the same are advanced between and withdrawn from the scrubbers, and means, substantially as shown, for supplying water to the bottles while being scrubbed and controlled by the movable support, substantially as set forth.

10. A machine for cleaning bottles, having scrubbers constructed and arranged for cleaning the outer surfaces of the bottles, and a frame located directly in front of the scrubbers and having an opening through which the bottles are passed for being scrubbed, substantially as set forth.

11. A machine for cleaning bottles, having scrubbers constructed and arranged for cleaning the outer surfaces of the bottles, a ring-frame located directly in front of the scrubbers, and a ring of smaller dimensions for removable attachment to the said ring-frame, substantially as set forth.

12. A machine for cleaning bottles, having scrubbers constructed and arranged for cleaning the outer surfaces of the bottles, a frame located directly in front of the scrubbers and having an opening for access to them, and a shield inclosing the scrubbers from the top and sides, substantially as set forth.

13. A machine for cleaning bottles, having scrubbers carried upon converging spring-arms attached to a revolving drum, a cup situated within and between the scrubbers and located upon a longitudinally-movable rod, means, substantially as described, for operating the said rod to support the bottles as they are advanced between and withdrawn from the scrubbers, a water-supply controlled by the movement of the rod, a frame located directly in front of the scrubbers and having an opening for access to them, and a shield inclosing the scrubbers from the top and sides, substantially as set forth.

14. A machine for cleaning bottles, having an expansible scrubber consisting of a hollow

stock, a brush mounted in the outer end thereof, and spring-arms secured to the stock and carrying scrubbers, substantially as set forth.

15. A machine for cleaning bottles, having an expandible scrubber consisting of a tapering hollow stock, a brush located in its forward end, and spring-arms secured to opposite faces or sides of the stock and carrying rubber scrubbers, substantially as set forth.

16. A machine for cleaning bottles, having an expandible scrubber, a rotary sleeve normally inclosing the same, a carriage carrying such sleeve and moved for uncovering the scrubber, a frame located directly in front of the scrubber and having an opening in it for access to the same, and a shield inclosing the

scrubber from the top and sides and attached to the frame, substantially as set forth.

17. A machine for cleaning bottles, having scrubbers for cleaning their inner and outer surfaces, located side by side, as shown, and water and operating connections for supplying water to the said surfaces of the bottles and for driving the scrubbers, substantially as set forth.

In testimony whereof I have signed this specification in the presence of two subscribing witnesses.

EDWIN S. PIPER.
